[57] CLAIM

The ornamental design for a storage chest, as shown and described.

DESCRIPTION

FIG. 1 is a front perspective view of a storage chest showing my new design, the rear of the storage chest being identical thereto;

FIG. 2 is a front perspective view thereof, the top in open position for convenience of illustration;

FIG. 3 is a front elevational view thereof; and

FIG. 4 is a side elevational view, the opposite side not shown being identical thereto. The bottom of the storage chest is plain and unornamented.

FIG. 1

FIG. 3
